(57) **CLAIM**

The ornamental design for a watch dial, as shown in the drawings.

DESCRIPTION

FIG. 1 is a front elevational view of the invention;
FIG. 2 is top plan view, the opposite side being a mirror image thereof;

FIG. 3 is a rear elevational view thereof;
FIG. 4 is a right side elevational view, the opposite side being a mirror image thereof;
FIG. 5 is an exploded perspective view thereof; and,
FIG. 6 is a bottom perspective view showing only the bottom plate, separated from the top plate for convenience of illustration.

The dot-dash line in FIG. 5 indicates that the top portion has been shown exploded away from the bottom portion and that the two parts line up on center when in non-exploded condition. The two tiny cylindrical protuberances seen in FIGS. 2 and 4 extend downward from the bottom of top plate in the space outward from and beneath the numbers "3" and "15" in the exact positions indicated in FIGS. 3 and 5.
